UNITED STATES PATENT OFFICE.

OLE OSTAD AND MAURITZ H. WELTA, OF FARWELL, MINNESOTA, ASSIGNORS
OF ONE-HALF TO CARL F. HAWKINSON AND MAGNUS HAWKINSON, OF
SAME PLACE.

ADJUSTABLE STOVE-GRAVE.

SPECIFICATION forming part of Letters Patent No. 624,673, dated May 9, 1899.

Application filed February 14, 1898. Serial No. 670,177. (No model.)

To all whom it may concern:

Be it known that we, OLE OSTAD and MAURITZ H. WELTA, citizens of the United States, residing at Farwell, in the county of Pope and 5 State of Minnesota, have invented certain new and useful Improvements in Adjustable Stove-Grates; and we do hereby declare the following to be a full, clear, and exact description of the invention, such as will enable 10 others skilled in the art to which it appertains to make and use the same.

Our invention relates to stoves of the class which have vertically-adjustable grates, and is directed particularly, first, to an improved 15 device for adjusting the grate as an entirety into different vertical positions and there holding the same, and, second, to an improved and simplified construction of the grate itself.

To the ends above indicated our invention 20 consists of the novel devices and combinations of devices hereinafter described and defined in the claims.

The preferred form of our invention is illustrated in the accompanying drawings, where- 25 in like characters indicate like parts throughout the several views.

Figure 1 is a side elevation of the fire-box end of a stove provided with our improved attachments. Fig. 2 is a vertical transverse 30 section of the parts shown in Fig. 1. Fig. 3 is a perspective view showing a portion of the grate-bar and the device for vertically adjusting the grate. Fig. 4 is a perspective view of a portion of the grate, some parts being partially and some wholly removed from working positions; and Fig. 5 is a horizontal section taken through a portion of the fire-box approximately on the line $x^5 x^6$ of Fig. 2.

1 indicates the main body portion of the 40 stove, which, as shown, is provided with a front end door 2, a side door 3, griddle-hole covers 4, and a fire-box 5, that extends downward to form the ash-pit 6 in which the ash-pan 7 is located. As shown in Fig. 5, the sides 45 of the fire-box 5 are formed with vertical corrugations 8, for a purpose which will herein- after more fully appear.

A single flat grate-bar 9 is passed entirely through the lower portion of the fire-box 5, longitudinally and centrally thereof, with its ends

working in and projecting through vertical slots 10, formed in the end plates of the firebox. The body of the grate proper is made up of a multiplicity of grate fingers or sections 11, that are provided at their lower ends with 55 perforated heads 12, that fit onto the common bar 9, the perforations in said heads being of the form of the cross-section of the bar 9, but slightly larger in order to give the fingers a slight rocking movement on the bar. These 60 fingers 11 as preferably constructed have the outline of a compound curve. When they are placed in working position on the bar 9, the adjacent members coöperate in pairs and form a grate that is approximately 65 Y-shaped in cross-section, one of the said adjacent grate-sections projecting to form one prong and the other projecting in an opposite direction to form the other prong or side of said grate. The stem portions of the 70 coöoperating adjacent grate-fingers 11 are cut away, as shown at 13, so that they overlap and interlock each other, and said fingers 11 are cut away at both sides, as shown at 14, so as to form draft-passages that extend across 75 the bottom of the grate, at some little distance upward on the prongs or sides of the same.

The ends of the grate formed by the sections or fingers 11 are closed by means of end plates 15, that are perforated and passed onto 80 the grate-bar 9 in a manner very similar to said sections 11. These end plates 15 work close to the ends of the fire-box 5 and are provided with depending tail-sections 16, that work over and keep the slots 10 always closed 85 under the adjustments or vertical movements of the grate. At its projecting ends, or just outward of the sides of the fire-box, the grate-bar 9 is provided with passages or perforations 17.

The device for vertically adjusting the grate 90 will now be described.

18 indicates a shaft which extends through the lower portion of the fire-box 5 parallel to the grate-bar 9 and is provided at its outwardly-projected ends with cam bars or rods 19, that are wound or turned upon themselves approximately on the line of an involute curve. These involute cam rods or bars work one through each of the passages or perfora- 100

tions 17 of the grate-bar 9, and the right-hand member is provided with a removable finger-piece 20, by means of which the said involute cam-bars 19 and shaft 18 may be rotated to 5 simultaneously raise or lower both ends of the grate-bar 9. In this manner, as is obvious, the grate as an entirety may be raised and lowered at will, so as to bring the body of burning coal or other fuel close to the top 10 of the stove or griddle covers 4 whenever it is desired. There is sufficient friction between the grate-bar 9 and the involute cam-bars 19 to hold the grate in whatever position it may be set. As shown, the cam-bars 19 are rigidly 15 secured to the shaft 18, and said shaft 18 is sectioned or divided at its central portion, as shown at 21, the parts being normally secured together by screws 22.

By reference particularly to Fig. 5 it will 20 be noted that the free ends of the grate fingers or sections 11 work in the corrugations 8 in the sides of the fire-box. These corrugations 8 thus serve as guides or runways for the said fingers. As the said fingers or sections 25 are loose on their bar 9, they may readily adapt themselves to these corrugations and will always run close to the sides of the fire-box. They will always bear against the sides of the fire-box, but will never tightly 30 press the same, and the action of expansion and contraction of the various parts will not increase or decrease this frictional engagement.

The importance of being able to readily adjust 35 the grate into different vertical positions or into different altitudes is well understood. It not only saves fuel, but it makes possible the most advantageous use of coal or fuel which may be left on the grate after the fire 40 has died down. It also makes it possible to get the greatest heating effect on the top of the stove from the burning fuel in whatever condition it may be.

The construction above described is very 45 simple, efficient, and of small cost. The grate sections or fingers may be readily replaced at any time, and the grate may be extended or contracted by adding to or taking from the number of sections or fingers employed. The 50 grate, as shown, is so constructed that it is adapted to burn either coal or wood.

It is important to note that the involute cam rods or bars 19 have a positive action on the grate-bar 9, so that the grate will be positively 55 forced down as well as up.

It will of course be understood that various alterations in the details of construction above specifically described may be made without departing from the scope of our invention.

The expression "stove" is used generically 60 and is intended to include ranges and similar devices. The expression "involute cam bars or rods" is intended to describe such bars or rods as are coiled or turned in a given plane in a manner which gives them approximately 65 or approaches an involute curve.

It would be within the scope of our invention to utilize the spiral or involute cam bars or rods even if the same were placed in the interior of the stove instead of outside, as shown 70 in the drawings.

What we claim, and desire to secure by Letters Patent of the United States, is as follows:

1. In a stove, the combination with the firebox thereof, of a grate provided with projecting perforated parts, and a grate-adjuster involving a shaft provided with a pair of involute cam rods or bars working with a cam action through the said perforated parts of the grate, substantially as described. 75

2. In a stove, the combination with the firebox thereof, of a vertically-adjustable grate provided with projecting perforated parts that work through vertical slots in the stove, and a grate-adjuster involving a shaft passed 85 through the stove and provided at its projecting ends with the involute cam bars or rods that work through said perforated projecting parts of the grate, substantially as described.

3. In a stove, the combination with the firebox thereof, of a grate involving the single bar 9 and the series of fingers or sections 11 loosely slipped onto said bar 9 in alternate order and forming a grate that is substantially Y-shaped in cross-section, substantially as 95 described. 90

4. In a stove, the combination with the firebox thereof, of the grate made up of the single bar 9, the grate-sections or fingers 11 loosely slipped onto said bar 9 and forming a grate 100 that is substantially Y-shaped in cross-section, and the end plates 15 also slipped onto said bar 9, substantially as described.

5. In a stove, the combination with the firebox thereof, formed with the vertical corrugations 8, of the vertically-adjustable grate involving the single bar 9 and the multiplicity of fingers or sections 11 loosely placed on said bar 9 and working with their free ends in said corrugations, substantially as described. 110

In testimony whereof we affix our signatures in presence of two witnesses.

OLE OSTAD.
MAURITZ H. WELTA.
